UNITED STATES PATENT OFFICE.

CHARLES OSBORNE, OF NEW YORK, N. Y., ASSIGNOR TO WHITING
MANUFACTURING COMPANY, OF SAME PLACE.

DESIGN FOR A HANDLE FOR SPOONS OR SIMILAR ARTICLES.

SPECIFICATION forming part of Design No. 34,400, dated April 23, 1901.

Application filed April 2, 1901. Serial No. 54,092. Term of patent 14 years.

To all whom it may concern:

Be it known that I, CHARLES OSBORNE, a citizen of the United States, residing in the city of New York, borough of Manhattan, in the county and State of New York, have invented and produced a certain new and original Design for Handles for Spoons or Similar Articles, of which the following is a specification, reference being had to the accompanying drawings, forming part thereof, and showing the design applied to a spoon.

Figure 1 is a view of the obverse, and Fig. 2 a view of the reverse, face.

The leading features of my design are the contour of the pronounced fiddle-shaped head and the shank, the prominent ornament at the junction of those members, the leaf-and-scroll ornament at the lower end of the shank, and the scrolls forming the outline of the head and flowing into the leaf ornament at the upper end.

At the junction of the shank and bowl is a drooping leaf flowing gracefully into the bowl contour and bearing a shell-like leaf. Immediately above is a double scroll, the volutes of which flank the upper portions of the leaf. The shank widens gradually from this point to the head and is ornamented with longitudinally-extending stems, the central pair bearing dependent leaf-buds arranged in pairs and overlapping upon the outer stems, which latter terminate in outwardly-curving small scrolls supporting the ornament at the junction of the shank and head. This ornament is similar in motive to that at the lower end of the shank, but is treated more elaborately to accord with its position and its prominence in the general effect. Its upper part is shell-

like and has a corresponding dependent leaf superposed upon a larger leaf marking the lower outline of the head. On each side of this ornament is an inturned volute, from which spring the upwardly-extending scrolls, following the margins of the head and merging gracefully into the shell-like leaf occupying the central upper portion of the head and surmounted by a scroll-and-flower ornament forming the terminal of the handle.

The space within the side scrolls is plain and is slightly convex on the obverse and concave on the reverse faces. Both faces are similar in general appearance; but the reverse is simpler in treatment and differs from the obverse in that the side scrolls terminate at the upper portion of a radially-marked shell, and a drooping leaf extends downward upon the bowl at the junction of the latter with the shank.

The several portions of the design are well-balanced and harmonious, and the ornamentation is in strong relief and definite outline, producing a peculiarly-pleasing effect of massiveness and grace.

It will be understood that the design may be applied to articles in all classes of table flat ware.

I claim—

The design for a handle for spoons or similar articles, herein shown and described.

In testimony that I claim the invention above set forth I affix my signature in presence of two witnesses.

CHARLES OSBORNE.
